E. SUTTER,
COLLAPSIBLE IRONING BOARD,
APPLICATION FILED JUNE 13, 1913.

1,156,643.

Patented Oct. 12, 1915.

UNITED STATES PATENT OFFICE.

EDWARD SUTTER, OF BURKE, SOUTH DAKOTA.

COLLAPSIBLE IRONING-BOARD.

1,156,643.

Specification of Letters Patent. Patented Oct. 12, 1915.

Application filed June 13, 1913. Serial No. 773,534.

To all whom it may concern:

Be it known that I, EDWARD SUTTER, a citizen of the United States, residing at Burke, in the county of Gregory and State 5 of South Dakota, have invented certain new and useful Improvements in Collapsible Ironing-Boards, of which the following is a specification.

This invention relates to an ironing board 10 or table having an attachment for supporting and heating the iron employed in connection therewith.

The object of my invention is first, to provide an improved ironing board of the above 15 mentioned type which may be collapsed or folded when not in use, second, to provide a simple and efficient heating attachment therefor, the latter likewise adapted to be folded upon the board when not in use, and 20 third, to provide means in the nature of spring arms or plates carried by the ironing board, and so disposed thereupon as to engage the fuel supply pipe of the heater, to not only retain the same when in use, but 25 to also serve as a retaining means therefor when in collapsed or folded condition.

The above and additional objects are accomplished by such means as are illustrated in the preferred embodiment in the accompanying 30 drawings, described in the following specification and then more particularly pointed out in the appended claims forming a part of this application.

In describing the invention in detail, reference will be had to the accompanying 35 drawings wherein like characters denote like or corresponding parts throughout the several views and in which;

Figure 1, is a side elevation of an ironing 40 board constructed in accordance with my invention; Fig. 2 is a top plan view; Fig. 3 is a side elevation showing the board and heater in collapsed condition; and Fig. 4 is a fragmentary view illustrating the manner 45 in which the fuel supply pipe of the heater is supported when collapsed. Fig. 5 is a perspective view of the bracket.

Referring now more particularly to the drawings wherein is illustrated the preferred 50 embodiment of my invention, the numeral 1 designates the ironing board proper, one end of which is tapered as at 2 for the obvious purpose of rendering the ironing of irregular material much easier. Pivotally connected as at 3 to suitable blocks 4

are the legs 5 of the board, the said legs adapted to cross about midway the length thereof when the board is in upright or operative position, one pair of legs carrying a pin 6 adapted to fit within cut out portions 60 7 formed within the opposite pair of legs, thereby supporting the board in the desired upright manner.

At one end of the board, a metallic plate 8 is secured, the said plate having an opening 9 formed therein beneath which a burner 10 is disposed, the latter being supported through the medium of a specially constructed bracket 11 adapted to be secured to the under face of the board 1, the said 70 bracket having oppositely disposed depending portions 12 formed integrally therewith through which an extension 13 of the fuel supply pipe 14 extends, the said extension being mounted for movement therein. Valves 75 15 and 16 are carried by the extension 13 for controlling the fuel supply from a tank 17 carried by the said pipe 14 above the board, the said supply pipe 14 when the fuel is in operative position extending vertically or at 80 right angles to the extension 13, the latter conveying the fuel within the pipe 14 to the burner 10 directly beneath the opening 9 of the metallic plate.

A resilient metallic spring arm 18 is secured to the board 1, the said arm having an offset portion 19 formed therein within which the pipe 14 is fitted for retaining or supporting the latter and the tank 17 carried thereby in an upright position, the free 85 end of the arm 18 being normally disposed in spaced relation to the edge of the board 1 so as to permit the said pipe 14 to be removed or withdrawn from the offset 19 during the folding or collapsing of the 90 heater. The pipe 14 having been removed, the same is swung with the extension 13 acting as a pivot until the tank 17 engages or nearly engages the board 1, the said tank when in this position being supported 95 by reason of a plate member 20, extending from the side of the board 1 and engaging the pipe 14 as illustrated in Fig. 4 of the drawings. As the tank and supply pipe 100 are moved with the extension 13 acting as a pivot, the valves 15 and 16 which also extend in axial alinement with the supply pipe are likewise moved so as to in no way interfere with the collapsing of the legs 5, 105 thereby permitting the entire device to be 110

easily collapsed so as to occupy a minimum amount of space and permit the same to be stored or transported with comparative ease. The position of the heater, with respect to 5 the board, will greatly facilitate the ironing operation and will also act as a rest for the irons when not in use, one iron being arranged over the burner, where it is heated, while the rest are placed upon the metallic 10 plate 8, thereby preventing injury to the board.

It will be seen from the above taken in connection with the accompanying drawings, that the entire board and attachment 15 employed in connection therewith may be completely collapsed or folded into a comparatively small device; that the spring arm 18 affords an efficient support for the fuel supply pipe 14 and tank 17 carried thereby; 20 and that the plate member 20 acts as a support for the said supply pipe when the heater is in collapsed condition.

It will be understood that the above description and accompanying drawings comprehend only the general and preferred embodiment of my invention and that various minor changes in the details of construction, proportion and arrangement of parts 25 may be made within the scope of the appended claims, and without sacrificing any of the advantages of my invention.

Having thus fully described my invention, what I claim as new and desire to secure by Letters Patent is:

35 1. In combination with a suitable support, a heater arranged beneath an opening formed in said support, a fuel supply pipe having an extension formed at one end thereof to which the heater is connected, a 40 bracket secured to the said support and adapted to surround the said opening to form a pivotal support means for the said extension of the fuel pipe, the said pipe adapted to be swung from its point of pivotal connection, as and for the purpose set forth.

45 2. In combination with a suitable support, a heater arranged beneath an opening

formed in one end of the said support, a bracket secured to the said support, the 50 bracket adapted to surround the said opening, said bracket having diametrically opposite depending portions formed integrally therewith, a fuel supply pipe having an extension formed at one end thereof adapted to 55 be pivotally supported by the depending portions of the said bracket, means secured to the said support adapted to engage the said fuel supply pipe for retaining the latter in vertical position, and means secured to said 60 support adapted to engage the said fuel pipe when swung out of vertical position for retaining the same in collapsed position, as and for the purpose set forth.

3. In combination with a suitable support, 65 a heater arranged beneath an opening formed within one end of the said support, a bracket secured upon the under face of the said support, said bracket surrounding the said opening, diametrically opposite depending portions formed integrally with the bracket, a pivotally supported fuel supply pipe having an extension formed at the lower end thereof adapted to extend through the said depending portion of the bracket, 70 the said extension of the fuel pipe forming a pivotal support for the heater, a spring arm having an offset formed therein, said arm being secured to the support adjacent said fuel pipe, the latter adapted to normally fit within the said cut out portion for positioning the burner directly beneath the said opening and in an operative position, and means including a resilient plate member secured to the said support, said plate member being 75 adapted for engagement with the said fuel supply pipe for supporting the same when in collapsed condition, as and for the purpose set forth.

In testimony whereof I affix my signature 80 in presence of two witnesses.

EDWARD SUTTER.

Witnesses:

HAROLD GRUNWALD,
CHAUNCEY DAY.
